UNITED STATES PATENT OFFICE.

CLIFFORD A. SWANK, OF DENVER, COLORADO.

WORD-DISPLAYING SIGNALING DEVICE FOR AUTOMOBILE CARS.

1,338,047.

Specification of Letters Patent. Patented Apr. 27, 1920.

Application filed October 21, 1919. Serial No. 322,241.

To all whom it may concern:

Be it known that I, CLIFFORD A. SWANK, a citizen of the United States of America, residing at the city and county of Denver 5 and State of Colorado, have invented a new and useful Word-Displaying Signaling Device for Automotive Cars, of which the following is a specification.

My invention relates to a word displaying 10 stop or turn signaling device for automotive cars, and the objects of my invention are:

First: To provide a signaling device adapted to enable a driver to signal other traffic, that he is about to stop or turn his 15 car.

Second: To provide a signaling device that can be operated from the driver's seat of an automobile and that is arranged to project from the side supports of the wind 20 shield of an automobile, or may be mounted on other suitable support or side or rear of car.

Third: To provide a double worded sign that will signal in the rear of the car provided with my signaling sign and also the 25 cars coming toward the car showing my signals.

Fourth: To provide a simple and practical substantially inexpensive stop or turn 30 signaling device that can be operated by hand or electromagnetic power.

I attain these objects by the mechanism illustrated in the accompanying drawings, in which—

35 Figure 1 is a side view of the signaling device, the slats being turned to display the word "Stop."

Fig. 2 is a similar view, the near glass plate, and its clamping frame being removed, the slats being in a neutral position, or in such position that no signal word is displayed.

Fig. 3 is a vertical transverse sectional view on the line 3—3 of Fig. 1, looking in 45 the direction of the arrow, X.

Fig. 4 is a similar sectional view on the line 4—4 of Fig. 1, looking in the direction of the arrow Y.

Fig. 5 is a sectional view on the line 5—5 50 of Fig. 1.

Fig. 6 is a detail end view, showing the spring by which the slats are returned to a neutral position when released from displaying either the "stop" or "turn" signal.

55 Fig. 7 is a sectional view of one end por-

tion of the device showing the operating shaft and its connection with one of the slats, the slat returning spring and the arm which engages the same.

Similar letters of reference refer to similar parts throughout the several views.

Referring to the drawings:

The numeral 1 designates a casing that has closed narrow side edge portions 2, and 3, and also end portions 4, and 5, upon the 65 outside edges of which are secured narrow frames 6, and 7.

The frames 6 and 7 support panes of 70 glass 8, and 9, which extend over and form the opposite sides of the casing.

These panes of glass are secured in position by the frames 6 and 7, which clamp them against cross pieces 11, and 12, by screws 10.

The plate 11 is spaced a slight distance 75 from the end 5, of the casing, and is secured thereto by screws 11^A, but the plate 12, is placed at a sufficient distance from the end 4, to leave a space for other parts of the sign which will be presently described. 80

A stem 15, is rotatably mounted in the end 4, of the casing and extends through and is rotatively mounted in a long bearing casing 13, which is provided with depending flanges 14, one of which is provided with 85 a set screw, 14^A.

The flanges 14, are arranged to straddle the upper edge of one side of the car, or a suitable support on the car, and the set screw enables the signaling device to be 90 rigidly secured to its support, and in this position projects laterally outward over the side of the automobile in plain view of the occupants of a car or cars in the rear of the sign.

The inner end of the stem 15, is formed with a square, axial hole in which fits a squared trunnion 16, that forms the pivotal support of one of the plates 17, the opposite end of which is also provided with a 100 trunnion 18, that is pivotally mounted in a bearing aperture in the cross plate 11, at the opposite end of and within the casing.

A crank lever 19, is secured on the trunnion 16, adjacent to the cross plate 12, and a 105 coiled spring 20, is also mounted on the trunnion 16, and its free ends 21, that extend from the opposite ends of its coiled portion and are under tension, bear against the opposite sides of a stop 22, with resilient 110

pressure. The stop pin is secured to the fixed cross plate 12, and the ends 21 of the spring, are engaged by an offset end 23, of the lever 19.

5 The ends 21, of the spring 20, are adapted to be engaged alternately by the end 23, of the lever 19, as the stem 15, is turned about a quarter of its full revolution in either direction by a reverse oscillating movement 10 which will be presently described.

On the inner side of the cross plate 12, and quite close to it, a connecting rod 27, is provided with an aperture that fits on a trunnion 28, that projects from the edge 15 of the blade 17, and which is positioned at a short distance from the pivotal trunnion 16, of this blade 17, and forms an eccentric trunnion to it. On each side of center blade 17, a number of swinging blades 29, of similar size and length as the blade 17, are placed, that also have short trunnions 30, which are pivotally mounted in apertures formed in the cross bar 12, to form bearings for them, and the opposite ends of each of 20 these blades 29, are provided with a trunnion 35, that are mounted in suitable bearing holes formed in the opposite cross bar 11, and all of these pivotally mounted swinging plates are positioned at equal distances 30 apart and they are of a width that allows them to overlap half the width of each blade when they are turned half way around in a semicircle in either direction until they all stand in a flat plane relative to each other, 35 in which position they have the appearance of a flat thin partition extending across the center of the length of the casing of the signaling device. These pivotally swinging blades are preferably made of thin metal, 40 but they can be made of any suitable material.

The connecting rod 27, that is pivoted to the trunnion 28, of the blade 17, is also provided with bearing apertures that fit over 45 the trunnions 28, of the blades 29, consequently all of the swinging plates are pivotally attached to the connecting rod 27, the ends of which do not extend to the inside walls of the adjacent side edges of the casing, consequently when the stem 15, is partially rotated in either direction through a half of a revolution, the center swinging plate 17, through the medium of its eccentric trunnion 28, and the free connecting rod 27, 50 which is mounted on the eccentrically positioned trunnions 28, of the other swinging plates 29, are reciprocated with an oscillating swinging movement from an open position, as shown in Fig. 1, to a closed or flat 55 position on either side of their open position by this connecting rod when the stem is turned rotatively about a half of a revolution in either direction, the engagement of the blades one against the other preventing 60 the swinging plates from being turned more 65

than a quarter of a rotative movement from the wide open position of the swinging plates relative to each other.

The stem 15, is locked in the two different opposite positions in which its words "Stop" 70 and "Turn" are displayed, by a pin 31 that is mounted in an aperture 32, that is formed in the stems bearing bracket 13, directly over the stem 15, which is provided with a hole 33, into one or the other end of which the pin 31, is sprung and held by a spring 34. The pin fits slidably in a gland 35, that is threaded into the aperture 32, which is threaded to receive it, and the outer end of the gland is provided with a knurled head portion that enables the gland to be adjustably screwed into its threaded aperture in the bracket. This gland is provided with an enlarged aperture in its inner end around the aperture the locking pin passes through, 80 in which one end of the spring is placed, and which acts as a housing for it. The opposite end of the spring 34, bears against a collar 36, that is formed on the inner end of the pin and forces it with a constant resilient pressure into the hole 33, in the stem. The outside end of the pin 31, is provided with a knurled disk 37, that enables it to be grasped by the hand of an operator and pulled out to release it from the hole 33, in 90 the stem.

On both sides of the swinging plates when they are turned or swung down into a flat position in one direction of their quarter part rotary turning movement, the word "Stop" 100 is painted or otherwise placed. Then when the plates are turned down the word "Turn" is painted or otherwise placed also on both or opposite sides, so that both words are visible from opposite sides of the sign, both 105 from the rear of the car on which my sign is placed, and also from the front of the car by automobiles coming toward the car carrying my double worded and displaying signal.

The outside end of the stem is provided with a hand grasping knob 38, that is used by the chauffeur to turn the stem 15, to display the Stop and Turn words. The operation of my improved Stop and Turn 110 word signaling device is as follows:

When the driver of a car provided with the improved signaling device desires to turn either to the right or left, he grasps the knob 38, and turns the same in the required direction until the spring controlled pin 31, springs into the hole 33, of the stem 15, and locks the same against rotation. The turning of the stem 15, swings the plates 29, into an overlapping position, whereby the word "Turn" is displayed from each side of the signaling device, so as to be seen both from the front and rear of the car, by the drivers of cars coming in either direction, and thereby noti- 115 120 125 130

fying them that the signaling car will turn at the approaching corner. Then when he has turned the corner he grasps the hand grasping disk of the locking pin and pulls 5 its inner end out of the hole in the stem, which will instantly release the stem and then the coiled spring 20, which was moved under additional tension by the engagement and movement of it by the end 23, of the 10 crank lever will throw the swinging plates backward into their non-word forming position. The signal word "Stop" is thrown into plain sight and released and moves out of sight in the same way, and is a signal to 15 cars following close behind him that he is going to stop.

My invention provides a positive and plainly visible "Turn" and "Stop" word signaling device for automobiles that can be 20 plainly seen for a sufficient distance in the day time to approaching cars, and at night it can be illuminated to show the words "Turn" and "Stop" by one or more suitably disposed electric lights placed 25 inside of the casing and electrically connected to a battery or a generator as is understood. The lighting feature, however, is not shown, as it is common to illuminate such signal devices.

Having described my invention, what I claim as new, and desire to secure by Letters Patent, is:

1. A stop and turn sign for automobiles comprising a casing provided with a plurality of swinging plates with the words Stop and Turn appearing thereon and means including a stem for turning said plates to display or not to display said words, said plates having the word "Stop" on 35 both sides of said plates when turned in one direction and the word "Turn" on both sides when turned in the opposite direction, for normally holding said plates in a non-sign displaying position, and means for locking said plates in the "Turn" and "Stop" sign word displaying positions, said non-sign displaying position of said plates being controlled by a stop in said casing, a spring arranged to engage the opposite sides of said stop, and means including a stem arranged to turn said plates and a crank lever secured to said stem and arranged to engage said spring, said plates being oscillatingly mounted at 45 their opposite ends, a stem secured to one of said plates, an eccentrically or laterally positioned trunnion on each plate at one side of the pivotal trunnion of each plate, and a connecting rod pivotally connected to 50 the eccentrically positioned trunnions of all of said plates, and arranged to move with them.

2. A stop and turn sign for automobiles comprising a casing provided with a plurality of swinging plates with the words

Stop and Turn appearing thereon, and means including a stem for turning said plates to display or not to display said words, said stem having a recess therein, and a hand operated spring controlled pin 70 adapted to engage said recess to lock said plates in signaling position.

3. The combination of the casing provided with the sign word plates arranged to swing from their separated edge viewing 75 appearing position into their flat side displaying position and having their opposite sides provided with the word "Stop" when turned on one side displaying direction, and with the word "Turn" when turned to their 80 opposite side position, with means including a bracket arranged to secure said casing to the side portion of an automobile, the stem extending through said bracket provided with a hand knob on its outer end, means at its inner end including one of said sign plates and a connecting rod attached to all of said plates for partially rotating them from their edge view position 85 into their sign word displaying position. 90

4. The combination of the casing provided with the sign word plates arranged to swing from their separated edge viewing appearing position into their flat side displaying position and having their opposite 95 sides provided with the word "Stop" when turned on one side displaying direction, and with the word "Turn" when turned in their opposite side position, with means including a bracket arranged to secure said casing to 100 the side portion of an automobile, the stem extending through said bracket provided with a hand knob at its outer end, means at its inner end including one of said sign plates and a connecting rod attached to all 105 of said plates for partially rotating them from their edge view position into their sign word displaying position, said stem being provided with a hole, a hand operating pin extending through said bracket to 110 enter said hole, and a spring to hold said pin in engagement with said stem and its hole, said hole and pin being arranged to lock said plates in their sign word displaying positions for predetermined periods of 115 time, and then released by withdrawing said pin from said notch into a non-sign word displaying position.

5. The combination of the casing provided with the sign word plates arranged to 120 swing from their separated edge viewing appearing position into their flat side displaying position, and having their opposite sides provided with the word "Stop" when turned on one side displaying direction, and with the word "Turn" when turned in their opposite side position, with means including a bracket arranged to secure said casing to 125 the wind shield portion of an automobile, the stem extending through said bracket 130

provided with a hand knob on its outer end, means at its inner end including one of said sign plates and a connecting rod attached to all of said plates for partially rotating them from their edge view position into their sign word displaying position, said stem being provided with a notch, a hand operating pin extending through said bracket to enter said notch, and a spring to hold 10 said pin in engagement with said stem and its notch, said notch and pin being arranged to lock said plates in their sign word displaying position for predetermined periods of time, and then released by withdrawing 15 said pin from said notch into a non-sign word displaying position, said non-sign displaying position of said plates being controlled by a stop in said casing, a spring arranged to engage the opposite sides of 20 said stop, and means including a stem arranged to turn said plates and a crank lever secured to said stem and arranged to engage said spring.

6. In a signaling device of the character 25 described, a casing, a plurality of blades having central trunnions on their opposite ends, and bearing supports for said trunnions, trunnions on said blades at one end, and on one side of the central trunnions, a 30 connecting bar in pivotal engagement with the latter trunnions, a coil spring on the central trunnion of one of said blades, the ends of which are extended, a stop against which the ends of said spring bear, a lever 35 rigidly mounted on the said central trun-

nion, having a right angled projection, which extends in between the ends of said spring, and means for turning said trunnion whereby all of said blades are turned in unison by said connecting bar, said blades 40 being arranged to overlap when turned, a signal word, displayed on each side of said overlapping blades, and spring controlled means for holding the blades in signaling position. 45

7. In a signaling device of the character described, a casing having bearing plates in its opposite ends, longitudinally arranged blades pivotally mounted in said bearing plates, means connecting said blades whereby they turn in unison, a turning rod connected with one of said blades, said blades being adapted to overlap half their widths, when turned in either direction, a signal 50 word displayed on each side of the overlapping plates when turned in one direction, a different signal word on each side of said overlapping plates when turned in the opposite direction, a spring controlled pin for engaging the turning rod at the limit of 55 its movement in either direction, a spring for restoring the blades to a non-signaling position, and means for actuating said turning rod.

In testimony whereof I affix my signature 60 in presence of two witnesses.

CLIFFORD A. SWANK.
